(57) **CLAIM**

The ornamental design for a scratch card and bottle opener, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever. FIG. 1 is a front perspective view of a scratch card and bottle opener.

FIG. 2 is a rear perspective view thereof.

FIG. 3 is a front side elevation view thereof.

FIG. 4 is a rear side elevation view thereof.

FIG. 5 is a top plan view thereof.

FIG. 6 is a bottom plan view thereof.

FIG. 7 is a right side elevation view thereof; and,

FIG. 8 is a left side elevation view thereof.
